UNITED STATES PATENT OFFICE

148,956

DESIGN FOR A COMBINED ARTICLE SUPPORT AND SEAT

Harold B. Rhodes, Hollywood, Calif.

Application October 25, 1946, Serial No. 134,244

Term of patent 14 years

(CL. D15—8)

To all whom it may concern:

Be it known that I, Harold B. Rhodes, a citizen of the United States, residing at Hollywood, county of Los Angeles, State of California, have invented a new, original, and ornamental Design for Combined Article Support and Seat, of which the following is a specification, reference being had to the accompanying drawing, forming a part thereof.

The figure is an isometric view of a combined article support and seat, showing my new design, a miniature piano, merely by way of example, being indicated in dotted lines as supported in operative relation to the seat.

The dominant feature of my design resides in the portions shown in full lines.

I claim:

The ornamental design for a combined article support and seat, substantially as shown and described.

HAROLD B. RHODES.
